TYPEWRITING MACHINE

William F. Helmond, West Hartford, Conn., assignor to Underwood Elliott Fisher Company, New York, N. Y., a corporation of Delaware

Application January 30, 1936, Serial No. 61,467

4 Claims. (Cl. 197—81)

This invention relates to typewriters and in particular to stop-devices for quietly arresting the movement of the platen-carrying frame at the ends of its case-shifting movements.

Heretofore, the shift frame, at the limits of its case-shifting movement, has engaged a yielding stop-member so that the impact of the blow is softened. These stops, being made of metal, depended upon the flexing of a yieldable portion for initially retarding the movement of the shift frame. Under repeated shifting of the frame, the stop is subjected to punishing blows and the constant flexing of the yieldable portion, as the frame comes into contact with it, tends to induce fatigue of the metal of said yieldable part. Instead of stopping the frame at a definite point, which is essential in aligning upper and lower case typing, the yieldable portion is liable to bend and gradually change the location of said 20 stopping point. Adjustment of the stop or complete replacement thereof would then become necessary in order to maintain upper and lower case alignment.

The present invention contemplates the use of a stop-device which embodies two resiliently yieldable extensions arranged so that either of them will take the impact of the blow of the shift frame to initially retard the movement of the frame and in so doing will flex slightly. This 30 flexing is a force-resisting movement of the stop extensions which slows down the movement of the shift frame, and as the extensions are free at their yielding ends from contact with a solid surface, the noise of the impact is deadened. This flexing, however, if freely permitted is liable to result in fatigue of the metal of the yieldable stop extensions and bending thereof, which is to be avoided. To prevent this bending, the extensions are arranged so that flexing movement 40 of one will cause it to engage or stub against the other extension so that both coact to resist any movement of the shift frame beyond the movement permitted by the flexing of the one extension receiving the impact of the blow of the shift frame. The stop member used is preferably made of strip spring-metal bent substantially into U-shape form with one of the legs, at its end, bent at right angles toward the outer end of the other leg so that either leg limits the 50 flexing movement of the other leg. Stop-forming ends of the legs are bent so that the body of the stop-member is inclined from said stop-forming ends, said body being mounted for endwise adjustment in the direction of its inclination. The 55 mounting means retains the stop in position so

that the stop-forming ends or extensions of the legs are engaged by the shift frame and are flexed thereby in resisting the impact of the shifting blow dealt by said frame. The temper of the metal of the stop may be such that both extensions, when they are in coacting relation, will provide a firm stopping agent for arresting the movement of the shift frame. When the shift frame, for instance, engages the lower extension of the stop near the end of a case-shifting movement, the single extension so engaged, will resist the blow of the impact of the frame but, due to the temper of the metal of the stop, will yield or flex slightly, but sufficiently to take up the main force of the blow. At the same time, the noise is lessened by avoiding the use of a solid sound conductor at the moment the frame engages the stop extension and the frame is stopped quietly and accurately. As the engaged extension flexes, the limiting lip or tongue thereon comes into contact with the under side of the upper extension and brings the frame to initial stop, the extension then coming to repose to definitely position the shift frame at proper case-shift position. The extensions acting singly will flex slightly under the impact of a blow, but when in coacting engagement with each other will form a firm initial stop for the shift frame. The flexure of either extension is so small that the elastic limit of the metal is not approached and the constant flexing through the small distance permitted by a small separation between the ends of the extensions does not cause fatigue of the metal. Thus no permanent bending of either extension results and the shift frame is brought to a stop at a definite point as defined by the position of repose of said extensions after its initial arrest by the coaction of both extensions.

The silencing of the blow of the shift frame is due to the use of tough, relatively thin, strip metal which, in its stop-extension portions, lacks the body to conduct sound as effectively as a solid stop-member. The flexing of the stop-extensions of the strip permits dissipation of the sound by giving way or yielding with the movement of the shift frame. The coactive engagement of the stop-extensions does not materially increase the sound conductivity of the stop because of the use of strip metal, but the flexing of the stop-extension to initially absorb the blow of the shift frame also serves to dissipate a large amount of sound that would result in the use of solid stop means. The initial flexing of the engaged stop-extension, therefore, not only

silences the blow of the shift frame, but also takes up the impact and prevents jarring of the frame.

The resilience of the extensions may be varied 5 by adjustment of the stop-device in the direction of its inclination because as the stop is adjusted back and forth on its support, the amount of overhang of the extensions is decreased or increased and the resilience of said extensions accordingly varied. The resilience of both extensions in coactive engagement, however, may be never insufficient to permit yielding of both simultaneously under the impact of a blow from the shift or platen frame. In addition, this end- 10 wise adjustment, due to the angle between the extensions and the relatively inclined body of the stop, provides means for varying the limits of case-shift.

In connection with the stop-device, use is made 20 of abutment or terminal screws for engagement with the stop-extensions. These screws are adjustable in an abutment bracket so that the range of case-shift may be varied, that is, the platen-shift frame may move a greater or a lesser distance depending upon the requirements, or either 25 case-position may be varied independently of the other. The adjustment afforded by the abutment screws is separate and independent from the adjustment that can be obtained by length- 30 wise movement of the stop-member on its inclined support, and means are provided in the nature of clamping sleeves on the abutment bracket for retaining the abutment or stop-screws in any adjusted position.

35 In order to cushion the parts of the platen-shift frame and carriage that meet when the platen frame returns to normal or lower case-position so that the sound is effectively deadened, means are provided for mounting a cushioning 40 pad in suitable ears at the rear of the platen frame, a feature being the construction and mounting of the cushion for use in the limited space afforded.

These devices are preferably mounted at the 45 front and rear of side-members of the platen-shifting frame as employed in Underwood typewriters.

This application is a continuation in part of my application Serial No. 3,037, filed January 50 23, 1935, now Patent No. 2,044,002, dated June 16, 1936. No claim is made to any feature of invention disclosed in the co-pending application of Ernest M. R. Borg, filed April 19, 1935, Serial No. 17,169.

55 Other features and advantages will hereinafter appear.

In the accompanying drawing,

Figure 1 is a view in perspective of a part of a typewriter showing the carriage and platen-shift frame and illustrating the mounting of the stop-devices.

Figure 2 is an enlarged view in side elevation, of one of the stop-devices shown in Figure 1, the yielding action thereof in arresting the shift frame for lower-case position being indicated.

Figure 3 is a view similar to Figure 2 showing the stop acting to arrest the frame for upper-case position.

Figure 4 is an end view in section of part of 70 the typewriter as shown in Figure 1.

Figure 5 is a view in perspective showing the separated parts of one of the stop-devices and means for mounting the same on the carriage.

Figure 6 is a view in perspective of one of the 75 cushion or buffer stops employed at the back of

the frame for supporting the same in lower-case position.

Referring to the drawing in detail, a carriage frame 11 runs upon a rear track 12 and front track 10. A platen 13 is journaled in a platen frame 14, supported in said carriage frame 11, for case-shifting movements, by means of side-arms 15 that are fastened to a cross-shaft 16 to work in unison. Said side-arms 15 support the platen frame 14 at gudgeons 18 of the latter, 10 and side-links 19, connected to the carriage frame 11, co-operate with said side-arms 15 to guide the platen frame case-shift movements. The usual key-controlled case-shift rail and its frame are shown at 20, Figure 4, the shift-rail engaging 15 a roller 21 of the platen frame. Ears 17, extending laterally from the sides of the platen frame, and having cushioning elements, to be described later herein, abut the carriage frame at 17a at the lower-case position of the platen frame. The 20 carriage moves in letter-feed direction upon actuation of the usual set of type-bars constituting type-carriers such as 22, provided with the upper and lower case types 23, Figure 4.

The means for varying the range of case-shift 25 movement of the platen frame and for arresting the movement quietly and without rebound of the frame will now be described.

Each platen frame side-plate 24 carries, at its front edge, spaced stop or abutment screws 25, 30 the opposed heads 25a of which are arranged to engage the opposite sides of a stop-member 32 carried on the carriage frame 11. The screws 25 in contacting the stop, arrest the movement of the platen frame 14 at upper and lower case 35 typing positions. In order to accurately adjust the printing point of the type-bars 22 at either upper or lower case position of the platen, the abutment screws 25 have threaded engagement with resilient clamping sleeves 26 of a U-shaped 40 abutment bracket 27. The bracket is riveted as at 28 or otherwise suitably secured to said platen frame side-plates 24. Each screw 25 may be slotted as at 29 in its opposite ends for convenience of individual adjustment in its respective sleeve 26. In order that the adjusted position of the abutment screws may be accurately maintained, the resilient clamping sleeves 26 which are formed integrally with the abutment bracket 27 are provided with tabs 30 which may 50 be moved toward the bracket 27 by the clamp screws 31 to constrict the threaded bore of the clamping sleeves 26 so that the abutment screws are gripped and prevented from jarring loose or moving with respect to each other. Release of the clamp screws 31 will permit the sleeves to open sufficiently to release their grip on the abutment screws 25 so that the latter can be adjusted as desired, but threaded engagement of the sleeves and screws is maintained when the 55 sleeves are in full open or release position.

The stop means employed for limiting the case-shift movements of the platen frame 14 includes the stop-member 32 made of strip or band metal into substantially U-shaped form providing upper and lower parallel legs 33 and 34 respectively. The ends of the legs 33 and 34 are bent at an angle and constitute upper and lower flexible leg extensions 35, 36 respectively. The lower extension 36 is bent at right angles to 70 provide an upstanding lip 37 which underlies the upper extension 35, is slightly spaced therefrom to form a gap and limits the flexing movement of both extensions 35 and 36. For instance, upon shift to upper case, the upper abut- 75

ment screw 25 engages the upper extension 35 of the stop 32 the extension will flex slightly as shown at 38, in outline, in Figure 2 to take the impact of the blow quietly but its flexing movement will be retarded by the limiting lip 37 with which said extension 35 comes into contact. As extension 35 comes into contact with the lip, the resistance of extension 36 is added to the resistance of extension 35 and the total resistance is such that practically no flexing of the coacting extensions 35 and 36 takes place and the platen frame is brought to an initial stop, the extension 35 then reflexing to repose position to finally stop the frame 14 at definite upper-case position. As the lower abutment screw 25 engages the lower extension 36, the latter is slightly flexed as shown at 39, in outline, in Figure 3 and takes up the impact of the blow quietly. The flexing movement is limited by contact of the lip 37 with the upper extension 35 to add the resistance of said extension 35 to that of extension 36 in bringing the platen frame to an initial stop, the extension 36 then reflexing to repose position to bring the frame to a definite stop in upper-case typing position. The gap between the lip 37 and the extension 35 is exaggerated as shown in Figures 2 and 3, and it is obvious therefore that said gap may be minute, say, one to three thousandths of an inch.

30 The mounting of the stop 32 on the carriage frame 11 is facilitated by an inclined groove 40 on said frame in which the stop 32 frictionally seats due to the resilience of its leg portions. The leg extensions 35 and 36, of the stop-member 32, through the medium of the bend previously referred to, are positioned preferably at right angles to and intermediate the abutment screws 25. Due to the relatively inclined position of the legs of the stop 32 with respect to the leg extensions, any movement of the stop in the direction of this inclination will adjust the leg extensions 35, 36 up or down and thus afford an added means of adjusting or varying the case-shift positions of the platen frame. The proper relation of the unengaged leg extensions 35, 36 is maintained by a spacer-block 41 of substantially the same width as the stop 32 and fitted closely between the legs 33, 34 thereof to prevent any flexing movement of the legs themselves. The spacer-block constitutes a pier-block 50 for the cantilever-like leg extensions 35, 36 which flex under the impact of the blow of the shift frame 14. The block 41 and stop 32 are secured in position by a screw 43 which threads into the carriage frame 11, as at 42, and is provided with an enlarged head 44 of sufficient diameter to overlie the edges of the stop 32 and constitute a clamping means therefor. The width of the stop is greater than the depth of the groove 40 and the edges of the legs protrude and are engaged by the screw head 44. Adjustment of the stop is made by loosening the screw 43 and sliding the stop 32 in the direction of its inclination and then tightening the screw, so that the head 44 thereof, in engaging the edges of the legs of the stop, holds the latter securely in place in the groove. Turning movement of the stop is also prevented by its close confinement in the groove.

70 Engagement of the platen-frame ears 17, formed upon frame-members 91, with the carriage frame at 17^a is cushioned for sound-deadening purpose by the following novel means arranged for application to the limited room afforded upon said ears. A thimble 92 rises from

the upper surface of the ear 17, and may be fastened to the ear 17. A cushioning pad 93, seated within a counterbore 94, at the bottom of said thimble 92, may abut the carriage frame at 17^a, said pad extending below the bottom surface of the ear 17. A screw 96 has a head 97 engaging the bottom of the pad to retain the latter against the counterbored seat of the thimble, and extends upwardly through the pad and through the thimble, so that a nut 98, threaded upon said screw and drawn against the top of the thimble, will co-operate to retain the pad 93. By variably drawing upon the screw 96 by means of the readily accessible nut 98, the pad 93 may be variably compressed, and thereby its extension 15 below the bottom of the ear 17 may be regulated to facilitate correspondence with the adjustment made at the front of the platen-frame to determine the lower-case platen-level. The ear 17 may also be bent up or down for adjustment of said platen-level.

Variations may be resorted to within the scope of the invention, and portions of the improvements may be used without others.

Having thus described my invention, I claim:

1. In a typewriter, the combination with a platen, spaced abutments, and a set of type-carriers, each type-carrier having a plurality of types, of a stop-device for quietly arresting the opposite relative case-shift movements of said platen and set of type-carriers, said stop-device including a stop-member presenting individually resilient extensions for yieldably resisting the impact of blows caused by contact of the abutments and stop-member, and means whereby said extensions are caused to coact to unyieldingly resist said impact and arrest relative case-shift movement of said platen and set of type-carriers.

2. In a typewriter, the combination with a platen, spaced abutments, and a set of type-carriers, each type-carrier having a plurality of types, of a stop-device for quietly arresting the opposite relative case-shift movements of said platen and set of type-carriers, said stop-device including a stop-member presenting individual resilient extensions for yieldably resisting the impact of blows caused by contact of the abutments and stop-member, and a projection on one of the extensions for engaging the adjacent extension whereby the extensions coact to unyieldingly resist said impact and arrest relative case-shift movement of said platen and set of type-carriers.

3. In a typewriter having upper and lower case types, a case-shift mechanism including, in combination, a case-shiftable frame, a pair of opposite case-shift abutments for limiting the case-shifting of said frame, a stop-member formed by a U-shaped resilient strip presenting individually yieldable legs for quiet engagement with said abutments, a lip on one leg for limiting the individual yielding movement of either leg by means of the other leg, to combine said legs in coactive relation to stop the case-shifts, and a support inclined relatively to said abutments for positioning the stop in inclined relation to its yieldable legs, said opposite abutments being adjustable relatively to one another to determine the extent of the zone of case-shift movement, and the stop-member being independently adjustable by movement along said inclined support for adjusting said zone relatively to the printing line of said types.

4. In a typewriter or the like; a stop device,

- usable for quietly arresting the opposite relative case shift movements of the platen and types, including a pair of opposite abutments, counter-stop means presenting two individually 5 resilient extensions between, and engageable each with a companion one of said abutments, and a projection on one of the extensions pro-

jecting toward the other extension so that either extension may stub against the other extension for limiting the flexing movement of either extension at its impact with its abutment, said extensions jointly resisting said impact when 5 one stubs against the other.

WILLIAM F. HELMOND.
